UNITED STATES PATENT OFFICE.

FRANK W. TICKNER, OF SHARPSVILLE, PENNSYLVANIA, ASSIGNOR OF ONE-HALF TO
FRANK J. LEUTHNER, OF BUFFALO, NEW YORK.

MOLDING APPARATUS.

1,274,107.

Specification of Letters Patent. Patented July 30, 1918.

Application filed April 23, 1918. Serial No. 230,366.

To all whom it may concern:

Be it known that I, FRANK W. TICKNER, a resident of Sharpsville, Mercer county, Pennsylvania, have invented a new and useful Improvement in Molding Apparatus, of which the following is a full, clear, and exact description, reference being had to the accompanying drawings, forming part of this specification, in which—

10 Figure 1 is a side elevation of a collapsing core barrel constructed in accordance with my invention; and

15 Fig. 2 is a central vertical section taken on the line II—II of Fig. 1, illustrating the core box in dotted lines.

20 My invention relates to collapsible core barrels, particularly those for casting ingot molds. It is especially designed to improve upon the devices of Patents 1,018,668, granted to F. X. Luethner and 1,018,669, granted to F. X. Leuthner and me on February 27, 1912.

25 The object of the invention is to improve the stop device for limiting the movement of the core plates, and at the same time prevent the sand molded around the core from entering the air spaces in the core during filling of the core box.

30 In the drawings, in which I show a form of collapsible core like that of Patent 1,018,668, 2 represents the central stem or column of the core barrel, which is shown as substantially rectangular in cross section and tapering from the bottom toward the 35 top in the form of a frustum of a pyramid. This stem is preferably hollow, though this is not necessary; and when hollow, it is preferably provided with a series of perforations and holes to assist in venting.

40 In the form shown, the sides of the core barrel are formed of four plates 3, which are arranged to provide air spaces, shown at 4, between the plates and the stem or central column. The lower ends of these plates 45 rest on flanges 5, projecting from the edges of the column 2, but are preferably secured to the column by cross bolts 6 and 7, at two different levels and extending through slots 8, in the column to allow movement of the 50 plate sides and column relative to each other. The plates may be recessed externally to receive the heads and counter-pins of these bolts, and I preferably provide two

sets of the bolts, one set in the upper portion and the other set in the lower portion 55 of the core.

The plate side portions of the core barrel are perforated for proper venting; and as thus far described, the device is similar to the patents above referred to. 60

Instead of the stops for limiting the upward movement of the core plates, such as shown in Patent 1,018,668 or Patent 1,018,669, I provide an improved stop system, comprising a lateral projection 9, sur- 65

rounding the upwardly projecting neck 10 of the column. This shoulder is above the upper end of the core box, shown in dotted lines at 11 in Fig. 2, during the molding of the core, and performs two important functions: first, it serves as a stop device for limiting the upward movement of the core plates, which, as they rise into the dotted position shown at 12 in Fig. 2, strike this stop device, thus giving a simpler and 70

cheaper stop system than in that formerly used; and second, it acts to shed the sand fed into the space between the collapsible core and the core box during formation of the core, and keep this sand away from the 75 air spaces between the plates and central column. In forming the core, the sand is ordinarily shoveled into the space between the core box and the core barrel before ramming, or otherwise packing the sand therein, and heretofore it has been impossible to keep this sand out of the air spaces. This 80 projecting ledge acts to shed this sand outwardly to keep it away from the air spaces and direct it into the proper space between 85 the core plates and the core box, thus preventing filling up of desirable air spaces and 90 wasting sand.

The advantages of my invention result from this sand-shedding device, which also 95 preferably acts as a stop for the side plates when the extractor shown in Patent 1,018,669 acts to eject the casting. The shedding device may be either circular, rectangular or of any other desirable shape. 100 The form of the core box, plates, etc., may be varied without departing from my invention.

I claim:

1. A collapsible core barrel having a cen- 105 tral column with a plate system movable

- thereon, and a shedding device on the upwardly projecting stem of the column arranged to protect the air spaces of the core from entering sand, substantially as described.
2. A collapsible core barrel having a central column with a plate system movable thereon, and a shedding device on the upwardly projecting stem of the column arranged to protect the air spaces of the core from entering sand, said shedding device also coating with the plate side structure
- 10

to limit its upward movement in extraction, substantially as described.

3. A collapsible core barrel having a central stem or column, and movable plate sides, the upwardly projecting stem of the column having a shedding flange arranged to be above the level of the core box and shed the entering sand away from the air spaces, substantially as described.

In testimony whereof I have hereunto set my hand.

FRANK W. TICKNER.
